LOYD A. BRIGGS, OF CRANFORD, NEW JERSEY, ASSIGNOR TO RADIO CORPORATION OF AMERICA, A CORPORATION OF DELAWARE

METHOD OF SIGNALING

Application filed August 13, 1928. Serial No. 299,219.

The present standardized method of signaling by keying a radio transmitter utilizes two signal values, that is a signal frequency for "marking" and no signal for "spacing" 5 or two signal frequencies, one for "marking" and one for "spacing". In this method of signaling which is known as the normal dot and dash method the length of a space between characters is equal to the length of a dot and the length of a space between letters is three times the length of a dot while the length of a dash is equal to three times that of a dot. In this method of signaling transmission involves the total loss of the time 15 used in spacing and also the extra time required to transmit dashes which take three times as long to send as a dot. The time utilized for spacing is wasted, i. e. the transmitting apparatus is idle during that time. 20 The primary object of this invention is to provide a method of signaling whereby the idle time used for spacing is usefully employed and the aggregate speed of transmission can be materially increased. 25 Briefly and broadly, this object is attained by utilizing the time which heretofore has been wasted by spacing, and by transmitting a dash which took a time interval three times the time interval required to send a dot. 30 This is accomplished by transmitting on a plurality of channels, three signal values being used on each channel. These three signal values are sent out on a single channel, according to the standard Morse code, and generally the dots are positive or of one frequency, the spaces are no signals or zero with reference to the dot while the dashes are negative or of a different frequency. For maximum efficiency five values of signal are used, 35 that is four signal values for marking and a fifth signal value for spacing. The use of five signal values as indicated above produces two channels and is required to secure full efficiency of the method. 40 For use on high speed transmitters, the number of signal values may be increased to seven, that is, six signal values for marking with no signal or the seventh signal value for spacing, or nine or even eleven signal values 45 or more to produce several slow speed chan-

nels. Where nine signal values are used, eight frequencies may be used for marking and no signal for spacing or a ninth frequency may be used for spacing. The use of seven, nine, eleven, or more signal values will 55 produce three, four, five, or more channels.

In each of the above cases the spacing or interval value may be no signal or an additional frequency depending upon the type of transmitter being used. The purpose of providing the odd or interval frequency is to 60 provide the interval between Morse characters in cases where such an interval occurs simultaneously on both channels.

Another object of this invention is to provide a novel transmitter which though simple in structure and operation will transmit signals on a plurality of channels according to applicant's novel method. 65

Preferably, I accomplished these objects 70 by the use of automatic transmitters at the transmitting end for keying the transmitter itself, each of which consists of a plurality of Wheatstone cable transmitters, there being one for each channel, driven by the same 75 motor and shaft, but otherwise entirely independent of each other.

A valuable feature of this invention is that transmission may be secret. This secrecy is afforded by transmission of dots and 80 dashes on two different frequencies and also by the fact that on successive days or hours or even shorter intervals the actual frequencies used for the dots and dashes of either signal channel and for intervals can be re- 85 assigned and used for different purposes.

A further advantage to be gained by the use of my novel method is that the signals transmitted according to this method may be received by aural reception, that is, by distinguishing the dots and dashes by their different tones, or they may be received by the use of an ink recorder. Both of these methods of reception are in general use and therefore signals sent according to my novel method 90 may be received by receiving apparatus now in use without materially altering said apparatus. 95

Other advantages will become apparent in part from the specification and in part there- 100

from when read in connection with the accompanying drawing by which the actual operation of this system can best be illustrated graphically.

5 Figure 1 illustrates graphically my novel method of transmitting; while

Figure 2 shows one arrangement of the apparatus necessary to carry out the novel method of transmitting illustrated by Figure 1.

10 In Figure 1 of the accompanying drawing, in which each section in a vertical direction represents one unit of transmitter time;

15 Line 1 represents the present normal method of signaling in which two values are used, usually signal and no signal and where a dash is three times the length of a dot.

20 Line 2, represents the cable method of signaling in which three values are used, usually positive for dot, negative for dashes and no signals for spaces.

25 Line 3—A represents the cable method applied to channel A of the improved method where frequency 1 is used for dots, frequency 2 for dashes and any other frequency or no signals for spaces.

30 Line 3—B represents channel B of the improved method where frequency 3 is used for dots, frequency 4 for dashes and any other frequency, or no signals for spaces.

35 Line 3—C represents the composite signal as actually transmitted into the air.

Line 4 represents the composite signal when transmitted after a reassignment of frequencies to obtain secrecy.

40 Lines 5—A, 5—B, and 5—C, show graphically my novel method of application to secure slower channels in words per minute with the same fundamental speed of transmission, while,

Line 5—D shows the composite transmitted signals of lines 5—A, 5—B and 5—C.

An explanation of my novel method whereby maximum efficiency is obtained will now be given. This method which utilizes five signal values thereby securing two channels will be sufficient to show the application of my method and advantages to be gained thereby. Since additional channels may be obtained by the use of additional signal values in the same manner that two channels are obtained by the use of five signal values an explanation of the method using five values and thereby securing two channels will be sufficient to show its application and advantage. The use of additional values to secure additional channels will then be self-evident it is thought.

Line 1 of the drawing represents the present normal method of signaling in which two values are used, usually signal and no signal and where the dash is three times the length of a dot.

85 Line 2 represents the cable method of signaling in which 3 values are used, usually,

positive for dots, negative for dashes and no signals for spaces. The word "silky" is shown in lines 1 and 2. However, it will be noted that the time required to transmit "silky" by the method used in line 2 is much less than the time required to transmit it by the method used in line 1.

70 In my improved method of signaling the standard Morse code is used on each channel employing one frequency for dots on "A" channel, a second frequency for dashes on "A" channel, a third frequency for dots on "B" channel and the fourth frequency for dashes on "B" channel. Dots and dashes are of equal length and are used as in cable practice, recording dots above and dashes below a center line. This in itself increases the speed of each channel by a well known percentage over that possible when the dash is three times the length of the dot. Each of the two channels will operate at the same speed possible on the single channel obtained by the usual two value method of signaling, and this without reducing the signal strength, signal-static ratio, or the length of dots and 80 space or their relative lengths or values.

85 Referring again to the drawing line 3—A represents the cable method applied to channel "A" of the improved method where frequency 1 is used for dots, frequency 2 for dashes and any other frequency, or no signals, for spaces. The word "silky" is shown.

90 Line 3—B represents channel "B" of the improved method where frequency 3 is used for dots, frequency 4 for dashes and any other frequency, or no signal for spaces. In this line the word "twelve" is shown.

95 Line 3—C represents the composite signal as actually transmitted into the air. As shown channels A and B of lines 3—A and 3—B respectively, are combined to send out the composite signals shown in line 3—C. The two frequency values on each of the channels A and B of 3—A and 3—B are denoted by the numerals 1, 2, 3 and 4 in line 100 110 115 120 125 130 135 140 145 150 155 160 165 170 175 180 185 190 195 is longer than the time required to send both words according to my novel method.

It is quite within the known range of a transmitter to produce and efficiently radiate 5 several different frequencies as the tuning values of the transmitter are altered by keying, and in carrying out my novel method of transmitting the several frequencies may be produced by altering the inductance or capacity values of the tuned circuits of the 10 transmitter. These frequencies differ from each other by several cycles, several hundred cycles or several kilocycles, depending upon the fundamental frequency employed. Thus 15 for an arc or tube transmitter on 16,000 cycles the five frequencies might be 16,100, 16,050, 16,000, 15,950 and 15,900 cycles, easily separated and distinguished at the receiver by well known methods of tuning and filtering.

20 For a short wave transmitter operating on 18,000 kilocycles, the five frequencies might be 18,004 kc., 18,002 kc., 18,000 kc., 17,998 kc., and 17,996 kc., also, easily separated and distinguished at the receiver by present methods 25 of tuning and filtering, and in this case allowing for a reasonable amount of frequency variation of the transmitter. It is therefore unnecessary to go into any further detail as to the transmitter itself or the receiver it- 30 self. The application of my novel method of transmitting may now be shown by considering the terminal apparatus at the sending end of the circuit and at the receiving end.

The automatic transmitters at the sending 35 end, for keying the transmitter itself will consist of two Wheatstone cable transmitters driven by the same motor and shafting or otherwise synchronized, but otherwise entirely independent of each other and being 40 controlled by a plurality of the usual perforated slips, the number of slips depending on the number of channels used. In the case where five signal values are used on two channels, two perforated slips will be re- 45 quired, one for each channel. The connection between the two Wheatstone cable transmitters and the motor will be such that the spacing interval of one coincides with the marking interval of the other.

50 A more complete understanding of the automatic transmitting apparatus and the operation thereof will be had from Figure 2 of the drawings, in which is illustrated one arrangement of apparatus used to carry out 55 my novel method. In this figure 1 and 2 are cable type Wheatstone transmitters controlled by two separate perforated slips, not shown, to transmit on channels A and B respectively. The transmitters 1 and 2 which 60 are otherwise independent of each other are driven in synchronism at the same rate of speed through gears 21 and 22 respectively by motor M. The connection between the automatic transmitters 1 and 2 and the gears 65 21 and 22 respectively on the motor shaft is

such that the spacing interval of one transmitter coincides with the marking interval of the other, and vice versa. That is, the plunger contacts of auto transmitter for A channel are always "up" when the plungers 70 on auto transmitter 2 for B channel are "down" and vice versa. The auto transmitters 1 and 2 are connected by wires 3, 4, 5 and 6 respectively to control relays 7 and 8 and, 9 and 10 respectively, which relays in 75 turn when energized close contacts 11 and 12 and, 13 and 14 respectively. In this manner the value of inductance 15 in the radio transmitter 16 is varied thus varying the frequency of the signal transmitted in accordance with the perforations in the perforated slips controlling the auto transmitters 1 and 2.

In the brief description of the keying operation of the auto transmitters which follows it will be assumed that dot elements represented by line 1 of channel A (line 3 Figure 1) are sent out at frequency f_1 which is the highest frequency used while the dash elements line 2 of channel A and dot and dash elements of channel B represented by lines 3 and 4 respectively are sent out on frequencies f_2 , f_3 and f_4 which decrease progressively or otherwise with respect to f_1 . A fifth frequency f_5 represented by line 5 of composite 85 signal 3C is used when a spacing interval occurs on channels 3A and 3B simultaneously.

In transmitting according to my novel method the words silky and twelve on channels A and B respectively under the above assumed conditions, the first signal element a dot of the letter s of silky (see lines 3A, 3B and 3C) on channel A is obtained by keying auto transmitter A to close line 3 (see Figure 2) energizing relay 7 to close contact 11. This short circuits a portion of inductance 15 and an electrical impulse at a frequency f_1 is sent out by transmitter 16. This signal element is represented by the first dash in 100 line 1 of the composite signal 3C. The next signal element a dash representing the letter t of twelve on channel B is obtained by keying auto transmitter B to close line 6, energize relay 10 and close contact 14. This 105 short circuits a small portion of the inductance 15 and a signal impulse at a frequency f_4 lower in this case than the frequency f_1 is sent out by transmitter 16. This signal element is represented by the first dash in 110 line 4 of the composite signal 3C. The next signal element a dot of the letter s of silky on channel A represented in line 1 of 3A is obtained by keying transmitter A to close contact 11. A signal element at frequency 115 f_1 is again sent out by transmitter 16. This dot on channel A is followed by a spacing interval which occurs at the same time as a spacing interval on channel B. This spacing interval (which occurred on both channels 120 130

simultaneously) is represented in the composite signal 3C by a unit in line 5 and is obtained when all of the contacts 11, 12 etc. are open leaving all of the inductance 15 associated with the transmitter 16 so that a signal element at frequency f_5 is sent out by transmitter 16.

As pointed out elsewhere in the specification the transmitters A and B are so coordinated and the strips so perforated that but one contact member 11, 12, etc. is closed at one time, and accordingly only a definite predetermined portion of the inductance 15 is short circuited at each keying operation.

These assumptions are made merely for purposes of illustration as it will be understood that various combinations of frequencies may be used on each channel, and that the interval value may be no signal.

The receiving end may be operated by the use of aural reception distinguishing the dots and dashes by their different tones, which is nothing new, or by the use of an ink recorder operating upward on the dot frequency and downward on the space frequency, this last method of receiving signals being also well known.

Actual reception of the transmitted radio signals may be accomplished by the use of a separate receiver for each frequency employed or, if the transmitting frequencies are sufficiently close to each other, two or more frequencies may be received on the same receiver and separated by tuning methods or by the use of proper audio frequency filters.

An illustration of the method of application to secure slower channels in words per minute with the same fundamental speed of transmission is illustrated in lines 5—A to 5—D in which 5—A shows channel A, 5—B shows channel B and 5—C shows channel C. The composite of the seven frequencies actually transmitted appears in line 5—D. In view of the detailed description of my novel method of transmitting signals by the use of 5 signal values on 2 channels as given above, this brief description of the method of adding channels by additional frequencies and the method of time division per channel will be sufficient.

A very valuable feature of this system is the comparative secrecy afforded by transmission of dots and dashes on two different frequencies and by the fact that on successive days or hours or even at shorter intervals, the actual frequencies used for the dots and dashes of either channel, and for intervals can be reassigned and used for different purposes, without any involved alteration in methods or apparatus at either end. For instance, when signaling, according to my novel method which uses five signal values on two signal channels, the frequencies 2 and 5 could be used for dots and dashes of channel A, frequencies 4 and 1 for dots and dashes

of channel B, and frequency 3 for intervals. The composite transmitted signal shown in line 3—C would appear when transmitted after reassigning the frequencies as suggested above as shown in line 4 of the drawing.

By the use of the so called cable code system combined with my novel method of utilizing the space interval of one channel as the signaling unit of a second channel, this novel method of transmitting gives a capacity of approximately two and one-half times the normal capacity of a transmitter without increasing the fundamental keying speed thereof. My novel method is also applicable to "channelling" whereby several slow speed channels are obtained, the total speed of all channels however totalling exactly the same as the two normal speed channels otherwise obtained by this method. The terminal apparatus is extremely simple and does not require synchronization of transmitting and receiving instruments.

Although described and illustrated herein in its specific application to radio communication my novel signaling method is equally applicable to communication over wire lines or cables. The same advantages of increased speed, increased capacity, and of multiplexing by obtaining several channels, are derived when applied to wire or cable communication as when used for radio communication.

What I claim is:

1. The method of increasing the speed of signaling which includes signaling simultaneously on a plurality of channels and utilizing the spacing time of one channel as the marking time of another channel.

2. The method of increasing the speed of signaling which includes signaling on a plurality of channels simultaneously and coordinating said signals in such a manner that the spacing units on one channel are utilized as the marking units on another channel.

3. The method of "cable code" signaling with auto transmitters which includes, signaling on a plurality of channels simultaneously, providing a plurality of frequencies for each channel for the marking units, and coordinating the keying of said auto transmitters in such a manner that the spacing units of one channel are utilized as the marking unit of another channel.

4. The method of signaling with auto transmitters which includes, signaling on a plurality of channels simultaneously, providing a plurality of frequencies for each channel for marking, providing a frequency for intervals and coordinating the keying of said auto transmitters in such a manner that the spacing units of one channel are utilized as the marking unit of another channel, and the interval frequency is utilized when a

spacing unit occurs simultaneously on all channels.

5. The method of signaling by means of a radio frequency transmitter controlled by auto transmitters of the cable type which includes, transmitting on a plurality of channels simultaneously, keying said auto transmitters to obtain a plurality of frequencies on each channel for marking, synchronizing said auto transmitters, and coordinating said auto transmitters so that the spacing units of one channel are used as the marking units of another channel.

6. The method of signaling by means of a radio frequency transmitter controlled by auto transmitters of the cable type which includes, transmitting on a plurality of channels simultaneously, keying said auto transmitters to obtain a plurality of frequencies, on each channel for marking, synchronizing said auto transmitters, keying said auto transmitters to obtain an interval frequency and coordinating said auto transmitters so that the spacing units of one channel are used as the marking units of another channel, and the interval frequency occurs when a spacing unit occurs simultaneously on each channel.

7. The method of cable code signaling with auto transmitters which includes, signaling on a plurality of channels simultaneously, providing a frequency on each channel for dashes, providing a frequency on each channel for dots, and coordinating said transmitters in such a manner that the spacing units of one channel are utilized as the dot and dash units of another channel.

8. The method of signaling by means of a radio frequency transmitter controlled by auto transmitters of the cable type which includes, transmitting on a plurality of channels simultaneously, keying said auto transmitters to obtain a frequency for dashes on each channel, keying said auto transmitters to obtain a frequency for dots on each channel, synchronizing said auto transmitters, and coordinating said auto transmitter so that the spacing units of one channel are utilized as the dot or dash units of another channel.

9. In radio apparatus the combination of a transmitter adapted to transmit a plurality of marking frequencies alternated with spacing frequencies on a plurality of channels, means comprising a plurality of automatic transmitters for controlling the frequency transmitted by said transmitter, and means for keying said auto transmitters in such a manner that the spacing units on one of said channels are utilized as the marking units on another of said channels.

LOYD A. BRIGGS.
